SOLDERING IRON TIP CLEANER

John Lee Race, Campbell, Calif., assignor to Lockheed Aircraft Corporation, Burbank, Calif.

Filed May 11, 1960, Ser. No. 60,541

Term of patent 14 years

(Cl. D9—6)

Fig. 1

Fig. 2

Fig. 3

FIGURE 1 is a perspective view of a soldering iron tip cleaner embodying my new design; and

FIGURE 2 is a front elevational view thereof; and
FIGURE 3 is a side elevational view thereof.

The characteristic features of my design for a soldering iron tip cleaner reside in the open box-like member thereof as best shown in FIGURE 1. The rear and bottom portions of the soldering iron tip cleaner are substantially plain.

I claim:

The ornamental design for a soldering iron tip cleaner, as shown and described.
